CARBURETOR

Charles O. Grosz, Wilkes-Barre, Pa.

Application August 25, 1932. Serial No. 630,462

5 Claims. (Cl. 261—14)

This invention relates to carbureting apparatus.

The principal object of the invention is to provide an apparatus and a process for the efficient admixture of two or more fluids to produce an explosive vapor.

Another object is to provide an improved hot air vaporizer whereby a volume of a pre-heated fluid, such as air, is mixed with a volume of another fluid, such as gasoline, to produce an explosive vapor.

Another object is to provide an apparatus embodying an improved assembly whereby pre-heated or unheated air, or the like, is drawn into a novel mixing head, there mixed with gasoline or the like, which has also been drawn into said mixing head and both ejected for employment as an explosive vapor.

Still another object is to provide a novel hot air vaporizer, embodying an improved assembly whereby air or the like is efficiently pre-heated prior to its admixture with a suitable hydrocarbon fluid either of a high, medium, or low grade, for producing an efficient explosive vapor.

Another object is to provide a novel carbureting apparatus embodying an improved assembly whereby a preliminary volume of air or the like is efficiently pre-heated prior to its admixture with a suitable hydrocarbon fluid and prior to the admixture of the thus mixed fluid with the main air supply.

Another object is to provide an improved device, in connection with a carburetor, to pre-heat a fluid to be mixed with the hydrocarbon fluid in the carburetor, said device being located close adjacent the carburetor and not inclosing or about the exhaust manifold of an internal combustion engine, which location frequently causes overheating of the exhaust manifold.

Another object is to provide a novel hot air vaporizer which is composed of few and easily assembled parts, and is inexpensive to manufacture and is of sturdy construction.

Other objects and advantages of the invention will be apparent from the following detailed description, taken in connection with the accompanying drawing forming a part of this specification and in which drawing:—

Figure 1 is an elevation of the improved apparatus attached to an internal combustion engine.

Figure 2 is a vertical section through the improved apparatus.

Figure 3 is an enlarged fragmentary vertical section through an improved mixing chamber and associated parts of the improved apparatus.

Figure 4 is a top plan view of the improved mixing chamber.

In the drawing, wherein like characters designate corresponding parts throughout the several views, the letter A indicates generally a motor vehicle, the letter B an internal combustion engine carried thereby, the letter C the improved apparatus attached to the internal combustion engine B and motor vehicle A, the letter D the pre-heating portion of said apparatus C, and the letter E the carbureting portion of said apparatus C.

The motor vehicle A may be of any approved construction and includes a suitable support such as a dash 10 provided with an opening 11 and a suitable number of perforations 12 for a purpose later described. It should be understood however, that the motor vehicle is not essential since it can be readily seen that the improved apparatus may be attached to a stationary internal combustion engine.

The internal combustion engine B is provided with a conventional exhaust manifold 15 having a conventional main outlet such as an exhaust pipe 16 and an auxiliary outlet provided by drilling or tapping the exhaust manifold as at 17 for a purpose later set out in detail. The internal combustion engine B is also provided with a conventional inlet manifold 18 having a suitable inlet pipe 19 terminating at its free end 20 with suitable means to attach a carburetor thereto. The internal combustion engine B is also provided with a suitable fuel supply line such as a pipe 21 having a union 22 for connection to the carbureting portion E of the improved apparatus C.

The improved apparatus C as heretofore brought out, includes the pre-heating portion D and the carbureting portion E and may be generally of any suitable material such as steel, brass, copper and the like.

The pre-heating portion D of the improved apparatus C includes a pipe or conduit 25 connected at its inner end to the exhaust manifold 15 preferably as shown at 17, so that a portion of the exhaust gases will travel from the exhaust manifold through the pipe 25. Connected to the outer end of the pipe 25 as by screw threads shown in Figure 2, is a valve 26 which may comprise a valve body 27 having a seat 28 and a preferably screw threaded valve head 29 ending in a preferably elongated stem or rod 30 which, in the case of the motor vehicle A, extends to the dash 10 where the rod is suitably connected to a handle 31 extending through the opening 11 in the dash 10 and surrounded by a sleeve 32 at

tached to the dash 10 as by screws 33 extending into the perforations 12. It can be seen that by turning the handle 31 the rod 30 and valve head 29 will revolve, the screw threads 34 in the valve head cooperating with the screw threads in the valve body, as is apparent from Figure 2, and the passageway 35 through the valve body will be adjusted thereby so that the volume of gases passing through the passageway may be varied.

10 Attached to the end 36 of the valve 26 as by screw threads is a pipe or conduit 37 which extends to a hollow heat-exchange member 40.

The heat exchange member 40 is preferably spherical and provides a closed chamber 41. The 15 walls of the member 40 are preferably rather thick although the member is not large as can be seen from Figure 1, and depending from the inner surface of the wall of the member 40 is a protuberance 42 provided with a screw threaded, 20 outwardly opening socket 43 as shown in Figure 2. A restricted passageway 44 extends from the inner end of the socket 43 through the protuberance 42 and opens into the chamber 41. Preferably axially aligned with this passageway 44 is a second passageway 45 of like diameter extending from the chamber 41 to the outside of the member 40. With their axes preferably at right angles to the axes of the passageways 44 and 45 are two other passageways 46 and 25 47 which may be opposite each other and which form an inlet (46) and an outlet (47), these passageways extending from the chamber 41 through screw threaded nipples 48 and 49 and a union 50 connects the end of the pipe 37 to the member 40 as shown in Figure 2, while a second union 51 connects the member 40 to a second pipe or conduit 52 which is adapted to lead the 30 gases flowing therethrough to any suitable place of outlet (not shown). A preferably screw threaded nipple or hollow connection 53 is provided and adapted to be attached to the member 40 from the socket 43 and protrudes therefrom, for a purpose later explained. It should be understood however, that this nipple 53 could be cast or otherwise formed as part of the member 40, 35 as are the nipples 48 and 49.

Extending through the member 40 and its chamber 41 is a pipe or conduit 60 with its opposite ends projecting beyond the member 40. The 40 pipe 60 extends through the passageways 44, 45 and through the passageway in the nipple 53 where it has a preferably fairly tight fit with the walls of the several passageways. From the 45 above and from Figure 2 it will be seen that gases forced through the pipe 37 will enter the chamber 41, strike the pipe 60, circle about it and flow out through the pipe 52. The gases do not flow along the pipe to any extent but rather strike it and flow about it. More will be stated relative to this conduit 60 in connection with a description of the carbureting portion E of the apparatus C.

The carbureting portion E of the apparatus C includes a carburetor of more or less conventional build. This includes a covered float chamber 61 provided with a conventional float 62 to regulate the liquid fuel level within the carburetor, and a liquid fuel inlet 63 from the outside and surrounded by a screw threaded nipple 64. The 50 nipple connects with the pipe 21 by the union 22. A fluid fuel passageway or channel 65 leads from preferably the base of the float chamber 61 in a generally horizontal direction to the mixing portion 65^a of the carburetor where it communicates with the passageway through an up-

wardly extending inner nozzle or spray head 66 which opens slightly below the mouth of an outer nozzle or spray head 67 surrounding the inner nozzle 66 and spaced apart therefrom. This outer nozzle 67 has communication with the channel 65 by way of a perforated compensator jet 68 and passageway 69, there being also a vertical well 70 communicating with the passageway and having a suitable air inlet. In addition to communicating with the passageway 69 the well 70 communicates with the compensator jet 68, and fills with fluid fuel from the float chamber. The nozzles 66 and 67 open upwardly into a venturi or choke tube 71, at the end of which is a butterfly valve 72. The outlet 73 above the butterfly valve 72 may be provided with a flange 74 and screw threaded openings 75 for attaching the assembly to the internal combustion engine B, in a manner which is well known. Leading from the atmosphere to the choke tube 71 is a main air inlet 76 and the volume of air taken in may be regulated by the butterfly valve 77.

Again referring to the conduit 60, it will be seen from Figure 3 that as it emerges from the upper end of the nipple 53 it flares out into a preferably funnel-shaped enlargement 80 which may be termed a mixing head and the chamber therein a mixing chamber 81. The circumference of the larger end 82 of this enlargement 80 is preferably substantially the outer circumference of the enlarged lower end of the inner nozzle 66 and the height of the enlargement that of the height of the passageway 65 so that the end 80 will prevent the conduit 60 from dropping out through the nipple 53 in one direction (downwardly, as in Figure 2 or 3) and when the enlargement is in place its upper end 82 will abut the end of the inner nozzle and block the way from the channel 65 to the passageway in the inner nozzle 66. However, a plurality of notches 83 are suitably made in preferably the end 82 of the enlargement 80 which form a plurality of spaced apart teeth or projections 84. Thus the notches may be said to form a plurality of restricted passageways between the channel 65 and the mixing chamber 81 and of course there is then communication established between the channel 65 and the passageway thru the inner nozzle 66. Preferably just below where the conduit 60 emerges from the lower end or bottom of the member 40, it makes a substantially right angular bend as at 87 and projects therefrom horizontally for a short distance and then makes another preferably right angular bend and extends upwardly ending in a goose neck bend 88 with the said bend above the normal level of liquid fuel in the float chamber and of course above the free end of the nozzles 66 and 67 as shown in Figure 2. The downwardly facing opening 89 at the end of the bend may be slightly flared and a filter screen (not shown) inserted for the purpose of excluding dust and other foreign matter. It is apparent that this conduit 60 may be integral or of several sections and at least the portions thereof within the member 40 should be of one of the metals which are good conductors of heat.

For the purpose of making a tight connection between the pre-heating portion D and the carbureting portion E of the improved apparatus C, a lock nut 90 may be provided for engagement with the nipple 53 and abutting the end of the carbureting portion as shown in Figure 2. However, it should be noted that the carbureting por-

tion E and pre-heating portion D of the improved apparatus C may be cast as one or otherwise made integral.

In the operation of the improved apparatus, it will be apparent that liquid fuel from the float chamber will seek its level in the well 70, the nozzles 66 and 67 and conduit 60 through the channels 65 and 69, compensator jet 68 and notches in the enlargement 80. When the internal combustion engine B is started the liquid fuel will be sucked from the conduit 60 to give the necessary rich starting fuel for mixture with the air in the choke tube 71 drawn in from the air intake 76 and that air will then enter the empty conduit 60 being sucked in by the vacuum created by the engine. This supplementary supply of air will mix in the mixing chamber 81 with the plurality of fine jets of liquid fuel also being sucked into the chamber 81 and be drawn through the nozzle 66. Opening the valve 26 will allow the hot gases from the exhaust manifold to flow through the conduit 37 and enter the pre-heating chamber 41 where they will strike the full length of the conduit 60 therein and heat the same which in turn will pre-heat the air passing through the conduit 60 so that this pre-heated air will mix with the fine jets of liquid fuel mentioned, heat the liquid fuel and thoroughly vaporize the same not only in the mixing head but also in the choke tube, so that there will be no raw fuel drawn into the intake manifold.

From the above, it will be seen that this preliminary supply of vaporized fuel is produced prior to its emergence from the inner jet and before it comes into contact with the other portion of the fuel and the air entering the air intake. The valve 26 of course permits the regulating of the volume of hot exhaust gases entering the pre-heating chamber and while the latter is relatively small and in no manner in the way nor cumbersome, it is particularly efficient since the hot gases do not travel along the conduit 60 nor deposit solids thereon, but strike against it and are aided in doing so, rather than hindered, by the protuberance 42.

It can be seen from the above that the air is pre-heated just before it mixes with the fluid fuel spray and does not have to travel a distance along a conduit or the like after it is pre-heated, thereby losing much of its heat.

The funnel-shape and location of the enlargement 80 not only provides a good mixing chamber and prevents the conduit 60 from dropping out, but any foreign matter, carried along the conduit 65 by the fuel, which may not settle into the cavity of the clean-out plug of the carburetor will be carried against the downwardly and inwardly sloping sides of the enlargement and settle at the base of the same from which place it may be removed as required.

Various changes may be made to the scope of the invention herein shown and described, without departing from the spirit of the invention or the scope of the claims.

63 What is claimed is:

1. In a carbureting apparatus, a carburetor having a fluid fuel passageway and a spray nozzle communicating therewith, and means for mixing fluid fuel and a second fluid adapted to promote the combustion of the fluid fuel, including a conduit for said second fluid, said conduit having a hollow enlargement at its end providing a

mixing chamber, said chamber having a volume greater than said conduit when measured equal height of said enlargement for equal height of said conduit, said enlargement carried within said fluid fuel passageway and opening into the passageway through said nozzle and provided with a restricted inlet for the fluid fuel from said fluid fuel passageway.

2. In a carbureting apparatus, a carburetor having a fluid fuel passageway and a spray nozzle communicating therewith, and means for mixing fluid fuel and a second fluid to promote the combustion thereof, including a conduit for said second fluid, said conduit having a hollow enlargement at its end providing a mixing chamber, said enlargement carried within said fluid passageway, said mixing chamber opening into the passageway through said nozzle and provided with a plurality of notches at its free end providing inlets for the fluid fuel from said fluid fuel passageway.

3. In a carbureting apparatus, a carburetor having a fluid fuel passageway and a spray nozzle communicating therewith, and means for mixing fluid fuel and a second fluid to promote the combustion thereof, including a conduit for said second fluid, said conduit having a funnel-shaped hollow enlargement at its end providing a mixing chamber, said enlargement carried in said fluid passageway and with its free end in abutment with the inner end of said nozzle and surrounding the end of the passageway through said nozzle, said free end of said enlargement having a plurality of notches, whereby fluid fuel from said fluid fuel passageway will have a restricted inlet through said notches to said chamber.

4. In a carbureting apparatus, a carburetor having a fluid fuel passageway and a hollow spray head communicating therewith, the axes of said passageway and hollow within said head being at substantially a right angle to each other, and means for mixing fluid fuel and a second fluid to promote the combustion thereof, including a conduit for said second fuel, said conduit having a hollow enlargement at its end carried in said fluid fuel passageway, providing a mixing chamber, and with the axis of said hollow enlargement substantially aligning with the axis of said hollow within said head, the enlarged end of said conduit in abutment with the end of said head and having a plurality of restricted passageways at its end in abutment with the end of said head, said restricted passageways providing a plurality of restricted inlets to said mixing chamber from said fluid fuel passageway.

5. In a carbureting apparatus, a hollow substantially spherical member, a conduit extending across the chamber within said hollow member and projecting without the same, means at one end of said conduit to receive fluid hydrocarbon fuel in a finely divided condition and mix therewith a second fluid flowing through said conduit, and means to convey a heated fluid through the interior of said hollow member in heat exchange relation with the conduit therein, including a pair of opposed passageways opening into said chamber, with their axes at substantially a right angle to the axes of said conduit within said chamber.

CHARLES O. GROSZ.
